UNITED STATES PATENT OFFICE

90,722

DESIGN FOR AN ATOMIZER

Florence N. Lewis, New York, N. Y.

Application January 20, 1933. Serial No. 46,895

Term of patent 7 years

To all whom it may concern:

Be it known that I, FLORENCE N. LEWIS, a citizen of the United States, residing at New York city, in the county of New York and State of New York, have invented a new, original, and ornamental Design for Atomizer, of which the following is a specification, reference being had to the accompanying drawing, forming part thereof.

I claim:

The ornamental design for an atomizer, as shown.

FLORENCE N. LEWIS.
